HANDLE ACCESSORY FOR WORK TOOLS

Robert John Reisner, 2064 Valley Lo Lane, Glenview,
Ill. 60025, and Michael Henry Andersen, 6948 Lexington Lane, Niles, Ill. 60646

Filed Aug. 13, 1973, Ser. No. 388,024

Term of patent 14 years

Int. Cl. D8—06

U.S. Cl. D8—1

FIG. 1 is a perspective view of a handle accessory for work tools with the bolts and snow shovel in broken lines for illustrative purposes only.

FIG. 2 is a side elevation thereof.

FIG. 3 is a bottom plan view thereof.

FIG. 4 is a top plan view thereof.

FIG. 5 is a rear elevational view thereof.

FIG. 6 is a front elevational view thereof.

We claim:

The ornamental design for a handle accessory for work tools, as shown.
